KITCHEN TOOL

Frank Marino, San Diego, Calif.

Application April 6, 1953, Serial No. 24,360

Term of patent 14 years

(Cl. D44—29)

To all whom it may concern:

Be it known that I, Frank Marino, a citizen of the United States, residing at San Diego, State of California, have invented a new, original, and ornamental Design for a Kitchen Tool, of which the following is a specification, reference being had to the accompanying drawing, forming a part hereof.

Fig. 1 is an isometric view of a kitchen tool showing my new design.

Fig. 2 is a plan view thereof.

Fig. 3 is an end elevation view thereof; and

Fig. 4 is a sectional view taken on the line 4—4 of Fig. 2.

The essential features of my design reside in those portions shown in full lines.

I claim:

The ornamental design for a kitchen tool, as shown and described.
